(57) **CLAIM**

The ornamental design for an injector cartridge, as shown and described.

DESCRIPTION

FIG. 1 is a side perspective view of an injector cartridge design;

FIG. 2 is a front side view of the injector cartridge shown in

FIG. 1, the rear side view being a mirror-image thereof;

FIG. 3 is a right-side view of the injector cartridge shown in

FIG. 1, the left-side view being a mirror-image thereof;

FIG. 4 is a top plan view of the injector cartridge shown in

FIG. 1;

FIG. 5 is a bottom plan view of the injector cartridge shown in

FIG. 1; and,

FIG. 6 is a bottom perspective view of the injector cartridge

shown in FIG. 1.

The broken lines shown in the figures are for environmental purposes only and form no part of the claimed design.

1 Claim, 5 Drawing Sheets
